UNITED STATES PATENT OFFICE.

ROBERT DONALD, OF LONDON, ENGLAND.

RESPIRATOR OR INHALER.

1,268,696.

Specification of Letters Patent. Patented June 4, 1918.

Application filed February 6, 1918. Serial No. 215,728.

To all whom it may concern:

Be it known that I, ROBERT DONALD, a subject of His Majesty the King of England, and resident of Highgate Road, in the county 5 of London, Kingdom of England, have invented certain new and useful Improvements Relating to Respirators or Inhalers, of which the following is a specification.

My invention relates to respirators or inhalers, and has for its object to provide such devices with an improved exhalation or non-return valve or valves that will be cheap to manufacture, simple in construction, efficient in operation, and not liable to be damaged 15 or put out of order by rough usage.

It is a particular object of my invention to provide an improved exhalation valve for the type of respirators illustrated by my U. S. Patent No. 1,229,050, of June 5th, 1917, 20 although the valve is equally adaptable to all gas masks or respirators which require a non-return exhalation valve.

It is to be understood that respirators are worn especially by soldiers during the so 25 called gas attacks, and that inasmuch as such gases as chlorin, bromin and many others equally dangerous are encountered, provision must be made to prevent even small amounts of such gases from entering 30 the nasal passage or throat of the wearer. Any one employing my device cannot by inadvertence or accident draw in air through the exhalation passage because of the instantaneous action of the flexible valve which 35 constitutes my present invention.

For respirators and inhalers there is an advantage in non-return valve action produced by the mutual pressure of smooth surfaces of flexible material such as oiled silk 40 or mackintosh or india rubber in the form of a tube collapsible under preponderating pressure exerted on the outer surface thereof.

The improved non-return exhalation valve provided by my present invention is in the 45 form of a collapsible cylindrical tube or sleeve having one of its ends secured to the respirator or inhaler and made of a fabric or material such as oiled silk, mackintosh, india-rubber or the like or other air-proof 50 material, which fabric or material is of such thin and flexible nature that the tube will readily open and distend to allow air exhaled in or from a respirator to enter the tube at the fixed open end and to pass out 55 through the distended tube, but will readily

collapse or fold upon itself when air attempts to pass in the opposite direction. In a respirator the fixed end of the tube or sleeve may be attached around an aperture in a mouth-flap strengthened if necessary at 60 the part. The tube or sleeve valve may for protection be inclosed more or less within a firmer outer tube, say of rubber, and the fixed end of the valve may be attached to the outer tube at or near one end, which the 65 wearer may take into his mouth.

My invention is hereinafter described with reference to the accompanying drawings in which:—

Figure 1 is a diagrammatic sectional side 70 elevation of a respirator or inhaler, showing the improved exhalation valve applied thereto;

Fig. 2 is an enlarged detail longitudinal sectional view illustrating the construction 75 of said valve and its arrangement within a protective tube, the valve itself being shown collapsed;

Fig. 3 is a transverse sectional view taken on the line 3, 3 of Fig. 2, and 80

Fig. 4 is a view illustrating a slight modification in the construction and arrangement of the valve.

As shown, the exhalation valve is in the form of a cylindrical collapsible tube or 85 sleeve *a* made of oiled silk or other thin and flexible fabric or material, which tube or sleeve, as illustrated in Figs. 1 to 3, is preferably secured within a firmer outer protective or reinforcement tube or mouthpiece *b* 90 of rubber or other preferred material, although this protective tube is not essential. The tube is passed through alined apertures in the inner and outer walls of the respirator, the construction of which does not differ materially from that shown in my former patent. In use the tube or sleeve valve *a* readily opens to allow the air exhaled from the mouth to pass out through the distended tube or sleeve, but collapses or folds upon 95 itself should the wearer attempt to draw air inward or in the opposite direction. The inner open end of the valve *a* may be secured to the inner end of the tube *b* by such means as adhesive material, or by stitching, or by 100 clamping it between the end of the outer tube and an inner ring *c* as shown in Fig. 2. If desired a simple tube or sleeve *a* may, as shown in Fig. 4, have its proximal end attached to an aperture *d* in the respirator *e* 110

the latter being strengthened at this part if necessary by such means as a short metal or other tube *f*, or the tube *a* may be attached to an aperture formed in a mouthpiece or flap of more or less firm substance such as metal or india-rubber stitched or otherwise attached to the respirator. In Fig. 4 the tube or sleeve *a* is shown extended, as by the force of exhalation from the user's lungs, in full lines, and in its contracted position in dotted lines.

The sleeve valve *a*, when inclosed within the outer tube *b*, is preferably and advantageously made so large that when distended it fills the outer tube. Such a sleeve valve *a*, when collapsed on itself, will be of a width too great to lie flat within the outer tube *b* but will lie around half the inner circumference of said outer tube as shown in Figs. 2 and 3 of the drawings. In order to aid the opposing surfaces of the valve to thus collapse during the use of the respirator, the valve may, in manufacture, be collapsed and fastened temporarily to a cylinder of a diameter substantially equal to the diameter of the outer tube. It is evident that a sleeve valve of this size in relation to the outer tube will have nearly $2\frac{1}{2}$ times the capacity of a sleeve valve that, when collapsed flat, would be accommodated on a diameter of the same tube.

What I claim is:—

1. In a respirator or inhaler a non-return exhalation valve in the form of a cylindrical collapsible tube made of such air-proof material as oiled silk, or india rubber, which material is of such thin and flexible nature that the tube will readily open and distend to its full cylindrical form to allow exhaled air to pass therethrough in one direction, and will readily collapse and fold upon itself to prevent air passing in the opposite direction, and means for securing the tube at one end only to the respirator.

2. A non-return exhalation valve for respirators, comprising an outer protective tube, an inner cylindrical collapsible tube, contained within the outer tube, the collapsible tube having an outside diameter equal to the inside diameter of the protective tube, and means for securing the two tubes to each other at one end.

3. A respirator comprising a body with inner and outer walls, an outer tube passed through the walls and having one end constructed to form a mouthpiece, and a cylindrical collapsible tube contained within the outer tube.

In testimony whereof I have hereunto signed my name.

ROBERT DONALD.
